UNITED STATES PATENT OFFICE.

CHARLES C. KLEIN, OF PHILADELPHIA, PENNSYLVANIA.

JOURNAL-BEARING FOR SHAFTS.

SPECIFICATION forming part of Letters Patent No. 225,224, dated March 9, 1880.

Application filed November 22, 1879.

To all whom it may concern:

Be it known that I, CHARLES C. KLEIN, of Philadelphia, in the county of Philadelphia and State of Pennsylvania, have invented certain new and useful Improvements in Journal-Bearings for Shafts, which improvements are fully set forth in the following specification, reference being had to the annexed drawings, in which—

10 Figure 1 is a side view, showing the improvements applied to a post-hanger, the journal-box being indicated in section through the line P Q, Fig. 6. Fig. 2 is a transverse, and Fig. 4 a longitudinal, section of the upper boss of the hanger. Figs. 3 and 5 show a modification of the adjusting and fastening device. Fig. 6 is a top view of the lower half of the journal-box, and Fig. 7 is a sectional view of the box through the line L M, Fig. 6.

15 The first part of my invention relates to that class of shafting-hangers known as "adjustable ball-and-socket bearings," in which the journal-box is suspended and held between bosses by plugs or short cylinders whose inner ends are provided with concave globular surfaces or their equivalents, and in which the journal-box is provided with convex globular projections or their equivalents, which match the surfaces upon the ends of the plugs.

20 The object of the first part of my invention is, first, to lessen the cost of the devices by which the vertical adjustment of the journal-box is accomplished by combining such parts and by making them of such shape that they will perform their function in their rough state, or, in other words, that only a comparatively small amount of machine-work shall be required upon them; second, to so combine a fastening device, K, with the adjusting device

25 that the strain of the fastening device upon the adjusting device E' or F' shall have a tendency to aid the adjusting device in the clamping of the box, while at the same time the adjusting device is prevented from becoming loose; third, to so combine the fastening device K, the drip-pan W, and the lugs T on the boss F that by the addition of a nut, K', the pan W will be firmly held and prevented from moving in any direction.

30 The second part of my invention relates, in general, to that class of shafting-hangers

known as "self-lubricators," and, in particular, to that kind in which the lubricant is drawn from a reservoir situate on a lower level than the shaft-bearing by capillary attraction; and the objects are, first, reduction in cost by constructing the journal-box and reservoir for the lubricant in such a manner that they can be cast easily in one piece, if desired, thereby doing away with the work of 60 drilling and tapping and saving the cost of screws or other fastening devices; second, greater efficiency, by placing the reservoir upon a higher level than has been possible in the devices now in use, thereby aiding materially the action of the capillary substance Y; third, greater convenience and accessibility by doing away with the necessity of tools for loosening the reservoir in order to be able to inspect its contents or the condition of the 70 capillary substance.

The objects of the first part of my invention are accomplished by providing, as usual, a plug, E', Figs. 1, 2, and 4, having upon its outer surface a screw-thread, and upon its inner end a concave globular depression, and upon its outer end a polygonal projection, or their several equivalents. The inner surface of the boss E may be cylindrical or polygonal, its office being simply to guide the plug E' in 80 a line at right angles with the horizontal plane of the axis of the shaft or journal-box, and for that reason the inner surface, of whatever shape its transverse section may be, must be parallel with the axial line of the plug, and 85 should be free from any projections or protuberances which would interfere with the free longitudinal motion of the plug.

A recess, O, Figs. 2 and 4, is provided in the boss E for the purpose of introducing into 90 it a section of a nut, I, fitting the screw-thread upon the plug E'. It will now be perceived that while before the introduction of the sectional nut I into the recess O the plug E' could be moved longitudinally, such motion 95 is no longer possible after the helical projections on I interlock with the threads on E', except by revolving the plug E' on its axis, when the usual action of the helix will manifest itself, and practically the effect will be 100 the same as if the whole interior of the boss E were provided with a screw-thread. While

the production of a screw-thread upon the interior of the boss E would be a comparatively expensive operation on machine-tools, the nut I with its helical projections can be formed 5 complete in the casting, and as such will not cost more than ordinary castings.

Let the plug E' now be revolved on its axis so that it will move toward the journal-box A; then that part of the surface of the screw-thread 10 which is toward the polygonal projection E', Figs. 1 and 4, will press against that part of the helical projection on I which is toward the journal-box; and if now both plugs bear against the journal-box, the tendency of the 15 screw K will be to force the plug E' yet tighter against the box by reason of the inclined sides of the threads and helical projections, and at the same time the plug E' is prevented from becoming loose.

20 By reference to Fig. 1 it will be seen that the axis of the fastening device K is parallel with the axis of the journal-box A, so that any strain brought upon the plug E' or F' by their fastening devices K will not force the axis of 25 the box A laterally out of its true position.

From the foregoing it will be evident that the sectional nut I is not intended to act simply as a washer for the screw K, to prevent the latter from bruising the threads on E', for I 30 am aware that pieces of a softer metal have heretofore been used for this purpose; but the piece I is to all practical intents and purposes a nut for the screwed plug E', and performs its functions as such in conjunction with the 35 smooth interior surface of the boss E.

In the boss F, Fig. 1, and in Figs. 3 and 5, a modification is indicated by which I am enabled to remove and introduce the sectional nut I without the necessity of removing F' from 40 F. The device in this form is also less expensive, as the drilling and tapping for the screw K, Figs. 2 and 4, are done away with, the hole for the bolt K, Figs. 3 and 5, being formed in the casting by coring. A nut is used in this 45 arrangement to hold and fasten the sectional nut I, as indicated in Figs. 3 and 4. A stationary nut, U, Fig. 3, is dropped into a recess in F, and answers the purpose of a head upon the bolt K. The latter is elongated beyond 50 this nut, and provided with a screw-thread for the purpose of holding the shank N of the drip-pan W and the nut K', which serves to fasten the shank N firmly to the boss F. It will be observed that by this arrangement the drip-pan W can be removed and attached without 55 interfering with the fastening of the nut I.

The thumb-nut K', Fig. 4, answers a purpose similar to that of the nut K', Fig. 5. A portion of the screw-thread on F' is removed, 60 and only so much of the central portion of F' is permitted to remain as will insure the necessary strength, the object being to allow the axial lines of K and F' to be brought as close together as possible.

65 The objects of the second part of my invention are accomplished by placing the reservoir B in such relative position with the axis of the

journal-box A that, first, the molds for the castings can be made without any unusual difficulty, and that the forming of the reservoir B 70 and the journal-box A in one piece, if desired, shall not add to the ordinary difficulties of forming the molds for the castings; second, that the vertical distance between the axis of the journal-box A and the level of the lubricant 75 in the reservoir B shall be reduced to its minimum; and, third, that the lubricant, residuary matter, and capillary substance Y can be inspected, removed, and replaced at any time without the necessity of using any tools 80 or implements to accomplish it.

It is the practice at the present time to arrange the reservoir for the lubricant vertically, or nearly so, below the journal-box, to which it is usually attached by screws, which latter 85 enter into holes provided with screw-threads in the metal between the top of the reservoir and the interior of the journal-box. The holes for these screws do not extend through to the journal-bearing, in order that the lubricant 90 may not leak through them, and for this reason a considerable thickness of metal is required between the journal-bearing and the top of the reservoir; hence the lubricant must 95 rise through the space occupied by this metal before it reaches the shaft, even when the reservoir is full to the top, and as the level of the lubricant falls the distance is increased proportionately.

In my invention the reservoir B is not placed 100 underneath the journal-box A, but is arranged at the side, and it also is raised until its top is about on a level with the lower part of the journal-bearing A; or, in other words, the reservoir B is displaced laterally from its usual 105 position for the purpose of making its molding in one piece with the box A without cores possible, and for purposes of convenience, and it is raised vertically, so as to decrease the perpendicular distance between the lower side of 110 the bearing and the level of the lubricant. Preferably, I place the top of the reservoir B slightly below the bottom of the journal-bearing A, as indicated by dotted lines x x, Fig. 7, for the reason that if it extended above it 115 and the reservoir was filled to its top through carelessness the lubricant would run out of the journal-box and be wasted.

By reference to Fig. 1, in which the box A and reservoir B and part of the plugs E' F' are shown in sections taken upon the line P Q, Fig. 6, it will be seen that the form and 120 position of the reservoir B are such that it will not only perform its functions, as specified hereinafter, effectively, but that also, during 125 the process of molding, the sand will leave the interior of the reservoir B as readily as it will the box A.

The channel D, running in an inclined direction from the reservoir B to the journal-bearing A, and into which the capillary substance Y is inserted, may either be cored or drilled.

The channels R, Fig. 7, running in an in-

clined direction from the annular channels S to the reservoir B, are intended to act as ducts to convey the lubricant from the journal back to the reservoir. These ducts are liable to be obstructed by dust and by matter loosened from the journal by abrasion, and it is important that they should be so arranged that they can be readily cleaned. In order to accomplish this in the present construction of capillary lubricators it is necessary to unscrew and remove the reservoir B from the box A, in order to be able to introduce a wire or other implement into the duct to remove the obstruction.

In my invention, by reason of the inclined position of the ducts R and the open flaring top of the reservoir B, the implement for cleaning the ducts can be introduced from that end of the duct which opens into the reservoir. The inclined position of the channel D also has the effect of aiding the capillary action of the wick Y to a considerable extent, owing to the fact that capillary attraction can be carried to a greater perpendicular distance by the aid of a number of short vertical distances in the form of steps than would be possible if the fluid had to rise to the same height in a single vertical line.

A further advantage of the inclined position of the channels D and R consists in the fact that the residuary matter, as particles worn off the shaft-bearing, dust, &c., which acts as a destructive agent upon the bearing, can leave the surface of the shaft promptly, flow with the lubricant back into the reservoir B, and settle there to the bottom, from whence it can be removed at convenient times. The open form of the reservoir B, unobstructed by adjacent parts, makes it possible to remove from its interior any foreign or residuary matter easily, to inspect, remove, or replace the capillary substance Y without the necessity of carrying or using tools during the operation.

From the foregoing it will be evident that this invention does away with the necessity of the curved channel which constitutes the subject-matter of Letters Patent granted to me February 11, 1869, as the entire reservoir B is placed in such a position that the lower boss, F, of a shafting-hanger cannot act as an obstruction to the continuation of the reservoir from one end of the journal-box to the other.

I am aware that heretofore journal-boxes have been made with vessels or pockets formed upon their sides similar to the reservoir described in this specification; but their function

was and is limited to that of a funnel, serving the purpose of introducing lubricant and regulating its level.

In my invention the reservoir B serves, first, to hold the entire body of the lubricant until the same is drawn away by the capillary substance; second, to receive the lubricant again after its circulation through the journal; third, to allow the residuary matter to subside upon the bottom of the reservoir and to permit its easy removal; fourth, to permit the introduction of new lubricant and the inspection, removal, or introduction of the capillary substance Y without the use of any tools. To perform all these functions effectively it is important that its position should be as indicated in Figs. 1 and 7.

In Fig. 1 the improvements are shown applied to a post-hanger; but it will be evident that the first part of my invention can also be applied to drop-hangers, wall-brackets, floor-stands, and pedestals or pillow-blocks, and that the second part of my invention will accomplish its objects as well on rigid bearings as it will on those whose boxes are provided with oscillating joints.

A loose cap, C, Fig. 1, prevents the introduction and accumulation of dust and other foreign matter in the reservoir B.

What I claim as my invention, and desire to secure by Letters Patent, is—

1. In an adjustable journal-bearing, the combination of the bosses E F, provided upon their interior with a smooth surface parallel with their axes, and plugs E' and F', provided upon their exterior with helical surfaces, with the sectional nut I, substantially as and for the purpose set forth.

2. In a journal-bearing, the combination of the drip-pan W, lugs T T, auxiliary nut K', and plug-fastening device K, substantially as and for the purpose set forth.

3. In combination with the journal-box A, having inclined channels R R, and with the capillary substance Y, the reservoir B, occupying in relation to the box A a lateral position, substantially as and for the purpose set forth.

4. In combination with the journal-box A, having inclined channels R R, capillary substance Y, and reservoir B, occupying in relation to the box A a lateral position, the loose cap C, substantially as and for the purpose specified.
